Application December 24, 1956, Serial No. 630,153

23 Claims. (Cl. 74—650)

2

of the side members, for instance, can be faced with a material of less strength than hardened steel, and that has improved friction characteristics.

A still further object of the invention is to provide a differential of the sliding block type having improved smoothness of operation.

Other objects of the invention will be apparent hereinafter from the specification and from the recital of the appended claims.

10 In the drawings:

Fig. 1 is an axial section of a differential constructed according to one embodiment of this invention;

Fig. 2 is a section taken on the line 2—2 of Fig. 1, looking in the direction of the arrows;

15 Fig. 3 is a fragmentary end view of a slightly modified form of driving member such as might be used in the differential of Fig. 1;

Fig. 4 is a fragmentary end view of a driving member of still another slightly modified form;

20 Fig. 5 is a diagram showing the preferred motion of the sliding blocks used in my differential, in terms of the relative turning displacement of a side member;

Fig. 6 is a fragmentary radial view of a side member and cooperating abutment portion of a sliding block constructed with radial teeth according to one embodiment of the present invention;

25 Fig. 7 is a fragmentary view similar to Fig. 6, but constructed according to another and preferred embodiment of the invention where the side members have spiral teeth;

Fig. 8 is a fragmentary view of the interengaging teeth of the members of Fig. 7 in a position of full depth engagement;

30 Figs. 9 and 10 are end views of the two opposite side members, respectively, of the differential such as shown in Fig. 1, looking at the toothed sides, and on a slightly smaller scale than Fig. 1;

Fig. 11 is a fragmentary end view looking at one end of the sliding blocks that are adapted to engage the teeth of the side members shown in Figs. 9 and 10;

35 Fig. 12 is an end view of the opposite ends of these sliding blocks;

Fig. 13 is a fragmentary view similar to Fig. 11, but illustrating a slightly modified embodiment of the sliding blocks;

40 Fig. 14 is a fragmentary section taken on the line 70 of Fig. 9 from the outside of the side member to the point of tangency 70 of the line 71 to the base circle of the involutes along which the teeth are curved longitudinally;

Fig. 15 is a somewhat diagrammatic view looking radially outwardly at the cylindrical inner ends of the teeth of the side members and of the cooperating sliding blocks, the view being developed into a plane, and the figure showing slightly more than half the circumference at said inner ends;

45 Fig. 16 is a diagrammatic view, similar to Fig. 15, but illustrating a modification of the sliding blocks;

Fig. 17 is a diagrammatic view, similar to Fig. 15, but showing a further modification;

50 Fig. 18 is a fragmentary section taken in the peripheral direction through the middle of a spiral tooth of a side member, and showing diagrammatically the direction of pressure exerted on that tooth;

Fig. 19 is a fragmentary normal section taken through the middle of a spiral tooth at right angles to the lengthwise direction of that tooth and showing a modified construction;

55 Fig. 20 is a view illustrating one way of producing the teeth of a side member, the side member being shown in section on a line tangent to the base circle of the teeth;

The present invention relates to differentials, and more particularly to differentials for use on automotive vehicles for connecting the two wheels of an axle, and for use between axles. In a more specific aspect, the invention relates to cam-type differentials of the axially acting type. Such differentials generally comprise a pair of coaxial side members having tooth-like projections, and a driving member coaxial therewith and containing blocks adapted to slide axially therein and to engage said projections.

Differentials of the kind referred to can be designed with a partial, or even complete, locking effect, so that loss of full traction on one of the driven wheels, for instance, of the vehicle leaves the other driven wheel with a multiple of the decreased traction of said one wheel; and the two driven wheels can still move with respect to each other, as required.

One object of the present invention is to provide a differential of the character described in which the interengaging projections of the side members and the sliding blocks have improved contact, so that the stresses at the contacting surfaces are reduced, with resulting increase in life, or load capacity, of the differential.

Another object of the invention is to attain this improved contact while achieving smooth motion of the blocks.

A further object of the invention is to provide a differential in which surface contact is obtained between the side members and blocks.

A further, and important, object of the invention is to provide a differential in which the side members and the blocks have projections or teeth that give a smaller end thrust at a given frictional braking torque, or locking effect, than known designs.

A related object of the invention is to provide a differential of the character described in which the blocks have spirally-arranged teeth at their ends for engagement with corresponding spirally-arranged teeth on the side members of the differential, and in which the hand of the teeth is so selected that the resultant loads exerted at opposite sides of each block are contained approximately in a plane.

Another object of the invention is to provide a differential of the character described in which the side members and the blocks have projections or teeth that can be produced with form tools, thereby simplifying their production.

To this end, a further aim of the invention is to provide a differential of the character described in which the side members and the blocks have projections or teeth which extend along such spirals that in any section perpendicular to the spirals the projections or teeth have a constant sectional profile from top to bottom. These spirals are involutes of a circle, coaxial with the axis of the differential.

Still another object of the invention is to provide a differential of the sliding block type with such low surface stresses on the contacting teeth that the teeth

Fig. 21 is a view of another form of tool that may be employed in cutting the teeth of the side members, the view looking at the cutting face of this tool;

Fig. 22 is a section, similar to Fig. 20, illustrating how a side member may be cut with another form of tool; and

Fig. 23 is a section taken at right angles to Fig. 22 and in the lengthwise direction of the teeth being cut, further illustrating the cutting process with the tool shown.

The differential of the present invention may be used as a power divider between pairs of driven wheels of an automotive vehicle, or also as a power divider between the two driven wheels of an axle; and it may be used in other installations, also, wherever a differential is required.

The embodiment illustrated in Fig. 1 by way of example is a differential for driving the two wheels of an axle. The differential, indicated generally at 39, comprises a centrally disposed driving member 31 which is rigid with a drive gear 32. The drive gear is here shown as a helical gear; but for passenger cars and light trucks a hypoid gear or other gear might be substituted for the helical drive gear shown. Gear 32 receives power in known manner from a helical pinion, not shown, that is operatively connected with a source of power.

Two end parts 33 and 34 are rigidly secured to the driving member 31 as by means of bolts 35 and nuts 36. They have seats 37 for suitable anti-friction bearings indicated diagrammatically in dotted lines at 38. Thus, the driving member 31 and the end parts 33, 34 form a rigid unit rotatably mounted in the bearings 38.

The driving member 31 is formed internally with straight axial grooves 40 (Fig. 2). These grooves are of circular arcuate profile, as denoted at 41. Sliding blocks 42 are movable in said grooves in the direction of the axis 43 of the differential. To save weight, the sliding blocks are recessed as denoted at 44. At their radially inner ends the blocks 42 bear against the cylindrical outside surface of a spacer ring 45 that is centered by the sliding blocks. At their two axially opposite ends, the blocks 42 contain tooth-like projections 46, 47 (Fig. 1) which are adapted to engage other tooth-like projections 48, 49 provided on two side members 50, 51. The sliding blocks 42 preferably have small clearance 52 (Fig. 2) relative to each other.

The driving torque passes through the contacting projections of the sliding blocks and side members. When the vehicle driven thereby moves in a straight path, the blocks are stationary in their grooves or ways 40 and the side members 50, 51 move together, without relative motion. When the vehicle turns a corner, however, the wheels move relative to each other, as do the two side members 50, 51; and as a result the sliding blocks reciprocate in the ways 40. The side members 50, 51 have splined connection with the axle shafts 53, 53', respectively, on which the two wheels of the vehicle are mounted.

Differentials having sliding blocks for connecting the two side members of the differential are known. The present invention resides chiefly in the shape and arrangement of the teeth of the tooth like projections 46, 47, 48, 49, of the sliding blocks and side members.

In the embodiment of the invention shown in Figs. 1 and 2, the ways 40 for the sliding blocks are arcuate in shape. Figs. 3 and 4 illustrate modified shapes of ways for guiding the sliding blocks. In Fig. 3, the driving member 31' is provided with a plurality of cylindrical holes 54 arranged in a circle about the axis 43 of the differential, that is, about the axis of the gear 31' and of the side members 50, 51. In this case, the sliding blocks are cylindrical in shape and reciprocate in the cylindrical axial guideways 54.

In Fig. 4, the driving member 31'' of the differential has slots 55 extending axially therethrough whose op-

posite sides are planes parallel to an axial plane of the differential. These slots are disposed at a constant distance from the axis 43 of the differential, and extend parallel to that axis. A central ring member 56 closes 5 the radially inner ends of the slots and completes the guide surfaces. The blocks, which reciprocate in the slots 55, are complementary in shape to these slots along the three sides of the slots, and are arcuate in shape at their radially inner ends to fit the ring 56.

10 Driving members, such as shown at 31' and 31'' in Figs. 3 and 4, respectively, may be used in place of the driving member 31 (Fig. 1) if desired, in all embodiments of the invention herein described.

Fig. 5 illustrates diagrammatically the preferred motion of the sliding blocks. The horizontal line, or abscissa 57 represents the relative turning angle of the side members 50, 51 of the differential. The vertical direction or ordinate of the composite curve 58 represents the displacement of a sliding block 42. The composite curve 20 58 is made up of distinctly different parts, such as part a—b, part b—c, part c—d and part d—a₁, between points d and a₁. The sum of these parts a—b—c—d—a₁ represents a complete cycle of reciprocation of the block.

It should be noted that the parts a—b and c—d are 25 straight. This signifies that the motion of the sliding block is in these parts directly proportional to the relative turning motion of the side members, that is, in these parts the sliding block moves uniformly upon uniform relative turning motion of the side members. These 30 portions are the working portions of the reciprocation cycle. The portions b—c and d—a₁ represent the reversal portions of the cycle of movement of the sliding blocks.

The constant proportion of the movement of the sliding blocks to the turning motion of the side members during the working portions of the cycle permits the use of helical surfaces on the sliding blocks and side members that have surface contact with each other, resulting in low surface stresses.

40 While the reversal portions b—c and d—a₁ occupy a smaller horizontal distance than the working portions a—b, c—d, they occupy a definite part of the total cycle, and are preferably at least half as large as the working portions. That is, the reversal portions b—c, d—a₁ occupy at least half as much relative turning angle as the working portions a—b, c—d of the side members. This is to make for smooth operation, without abrupt changes of motion.

Fig. 6 affords an end view of the teeth 48 of a side member 50 and a tooth of a sliding block 42, when the teeth of the block and of the side member are straight radial teeth. The view is from the outside looking toward the axis 43 of the coaxial members. Points a', b', c', of the profile 60 at the outer ends of the teeth of the side member 50 correspond, respectively, to the points a, b, c of the motion diagram of Fig. 5. Points a'', b'', c'' of the profile 61 at the inner end of the teeth of the side member 50 correspond, respectively, to points a', b', c', of the outer profile, and to points a, b, c of the motion diagram. The portion a'—a''—b''—b' of the side surface of tooth 48 of member 50 is a helical surface of constant lead. It is matched to the depth of engagement by a counterpart helical surface of constant lead provided on the tooth 46. This tooth is shown in engagement with a portion of the area a'—a''—b''—b' in surface contact.

70 The outer and inner profiles 60, 61 of the tooth surface of the tooth 48 lie in cylindrical surfaces coaxial with the axis 43 of the differential. When the cylindrical surfaces of these profiles and of intermediate profiles are developed into a plane, their profiles have the same extent in the axial, or vertical, direction, but occupy different distances in the peripheral, or horizontal, direction. The various profiles differ from each other, but 75 can be derived from the outer profile by contracting its

horizontal scale. This applies to the teeth 46 of the sliding block as well as to the teeth 48 of the side member 50, and to the teeth 47, 49 on the opposite side of the sliding block and on the opposite side member 51.

It should also be noted that the concave arcuate portion 62 at the tooth bottom extends through a peripheral distance at least twice as large as the convex arcuate portion 63 at the tooth top. The teeth 46 of the blocks 42 have this same characteristic. Thus, in the position of closest approach of the sliding blocks to side member 50 (Fig. 8) only the arcuate portions 64 of the teeth 46 and the arcuate bottoms 62 of the tooth spaces of the side member 50 are in contact, while the sides of the teeth of these members are separated from each other.

The variation in the profiles lengthwise of the teeth presents difficulties to efficient and accurate manufacture. One possible way of avoiding such difficulties is to provide teeth or projections on the sliding blocks, each of whose tooth sides is a single simple surface of revolution adapted to contact a mating tooth surface of a side member. Such a surface may be completely described by a rotary tool.

Convex spherical surfaces, or convex cylindrical or conical surfaces, are such known surfaces, some of which have been used in connection with side members for differentials such as disclosed. The ribbed or undulatory contact surfaces of the side members can then be produced by generation with a rotary tool that describes such a surface of revolution of a sliding block. As the tool rotates on its axis, the side member to be cut is turned slowly on its axis, and the tool is advanced axially, as if the sliding block would engage and mesh with the side member.

While this procedure solves the manufacturing problems, the contact between the sliding block and the guide member is far less intimate than with the structure here proposed. Also, surface contact is impossible. The surfaces are stressed severely in operation, causing wear.

It has also been proposed to leave out the arcuate portions 62, 63, entirely, and let the opposed helical surfaces of the teeth come to a sharp radial edge. This causes very abrupt reversal of the sliding block motion with extreme accelerations, and knocks. Also, this proposal solves only a part of the manufacturing problems, for according to the known practices, the helical surfaces with their change in profile inclination along the teeth still present obstacles to efficient manufacture.

The manufacturing problems and other problems are solved by the present invention by using spirally arranged teeth 48', 46' (Fig. 7) on the teeth, and particularly by providing teeth that extend lengthwise along involute curves. Their end profiles may be the same as the end profiles of the straight teeth 48, 46 of Fig. 6. Likewise, the profiles in the intermediate cylindrical sections coaxial with the differential may be the same.

In the preferred embodiment of the present invention, then, the side surfaces of the teeth of both the blocks and the side members are helical surfaces of constant lead joined by rounded tips and by rounded tooth bottoms, and the rounded tooth bottoms have an angular width at least half as large as the angular width of the side surfaces of the teeth, and at least twice as large as the angular width of the tips or outer profiles of the teeth.

In Figs. 9 to 12, the tips 63 of the teeth are shown in heavy lines and the tooth bottoms 62 in finer lines. The teeth 48' of the side member 50 extend along involutes 68 of a circle 67 concentric with the side member 50 and coaxial with axis 43. Two such involutes 68 are shown extended beyond the region of the teeth in Fig. 9 to show them up more clearly. The top ends 63, as well as the bottoms 62, are all involutes of the base circle 67. Moreover, all planes perpendicular to the axis of the side member 50 within the tooth region intersect the teeth in involutes of the same base circle.

As known, all tangents to the base circle 67, like the tangent 70, are perpendicular to all the involutes they intersect. They are normals of the involutes.

An involute can be considered described by a point of a string that is unwrapped from the base circle. The point of contact 71 of the string or tangent 70 with the base circle 67 is the curvature center of the involute at the considered point of the involute. Involutes have a constant normal pitch. That is, any two involutes have a constant distance from each other all along their length. An important feature is that the normal distances between the adjacent tooth tops 63 is constant along the length of the teeth, see Fig. 14, which is a normal section through the teeth, a section along the tangent 70. The composite profile 73 of a tooth space is constant in all normal sections along the teeth, while it is only the profiles in cylindrical sections coaxial with the axis 43 of the side member that change. This removes the chief manufacturing difficulty, as will be described further later.

The involute helicoid of constant lead contains a straight sided profile in normal section. Thus, the working portions 72 of profile 73 (Figs. 14 to 19) are straight, and have a constant inclination to the axis 43 of the differential. The arcuate connecting portions 62, 63 serve for the reversal of the motion of the sliding blocks, and are in contact during such reversal. They are preferably made circular arcs. The radius of the concave arc 62 is at least twice as large as the radius of the convex arc 63.

It should be understood that in place of exact involutes, approximation may also be used, to achieve at least a good part of the effect. For instance, an involute 68 might be replaced by a circular arc centered at the curvature center 71 of the involute; and the side surface of a tooth 48, might, therefore, be a surface of revolution, of which the straight sided working portion is part of a conical surface.

The use of spiral, or spirally arranged, teeth, in accordance with the invention, achieves a further important advantage. It reduces the end thrust required to achieve a given internal braking or locking effect. This is shown diagrammatically in Fig. 18, which is a section coaxial with axis 43 taken midway through a spiral tooth 48'. Point 74 denotes the mean point of tooth engagement in the region shown. If the friction is zero, the pressure exerted upon the tooth would be perpendicular to the tooth surface. It would be in the direction of the tooth surface normal 75 shown in projection in Fig. 18, and at right angles to the profile 76 of the tooth in this section. The normal 75 is inclined to the drawing plane increasingly with increasing spiral angle of the teeth. It would lie in the drawing plane only if the tooth were straight.

Only the peripheral component 77-74 of the tooth pressure produces torque. On straight teeth, the normal tooth pressure at zero friction and with a given peripheral components 77-74 would be measured by the distance 78-74. With spiral teeth, however, the normal tooth pressure is larger. Distance 78-74 represents only its projection to the drawing plane. Thus, if the inclination of the surface normal to the drawing plane were 45°, or 60°, the normal pressure would be represented by the distance 78-74 divided by cos 45° or cos 60°, respectively. It would amount to 1.41 times or twice, respectively, the normal pressure on straight teeth.

The frictional force that opposes relative sliding of the contacting teeth of the profile 76 increases with increasing normal pressure, about in the same proportion as said pressure, while the axial thrust component of the normal tooth load remains the same. This thrust component is represented by distance 77-78 that extends in the direction of the axis of the differential.

Depending on the direction of sliding, tooth loads result that are inclined to the direction of the normal 75,

the load 80' exerted on the spiral teeth appearing more inclined than the load exerted on straight radial teeth.

With spiral teeth, the inclination of the normal tooth profiles 72 (Figs. 14 and 19) towards one another and towards the axis of the differential is smaller than the inclination of the profile 76 of the peripheral section (Fig. 18). Opposite working portions 72 of profile 73 include an angle with each other, preferably smaller than a right angle. They also include an angle preferably smaller than half a right angle with the direction of the axis 43 of the coaxial members of the differential.

The spiral teeth 48', 49' (Figs. 9 and 10) of the side members 50, 51 are of opposite hand, in accordance with the invention, the teeth on one member being of right hand and the teeth are on the other member of left hand. Likewise, opposite ends of the sliding blocks 42 have teeth of opposite hand (Figs. 11 and 12).

The hand is defined by locking at the toothed ends. If the teeth of both sides of a sliding block are visualized as looked at in the same direction, however, one side from the front and the other side from the rear, the hand of the teeth would appear to be the same. Thus, when looked at in Fig. 11 the teeth 47' (Fig. 12) of the sliding block 421 would appear to coincide with the teeth 46' of that sliding block. This means that the normal forces exerted on the tooth surfaces at the front and rear of each sliding block lie approximately in a plane. The blocks are well mounted in their guide surfaces since there are no appreciable moments tending to tip the blocks.

Fig. 11 shows the teeth 46' of the blocks 42 that engage the teeth 48' of the side member 50 (Fig. 9). Fig. 12 shows the teeth 47' of the blocks 42 that engage the teeth 49' of the side member 51 (Fig. 10). The teeth are preferably chamfered at their acute ends, wherever necessary. Thus, in Figs. 9 and 10, 81, 82 indicate the chamfered portions at the outer and inner ends of the teeth.

Fig. 13 illustrates a modification of the invention in which the sliding blocks 42a have cylindrical outside surfaces 84 with arcuate recesses 85. A central member 86 then retains the blocks in their proper radial positions.

The end of a sliding block contains preferably more than a single tooth. Thus, the blocks 42 all contain two teeth 46'. These teeth are disposed alike on one end of all the blocks. On the opposite ends of the sliding blocks 42, the teeth 47' are arranged in two different patterns. The teeth 47' of the blocks 421, 423, 425 and 427 are identically disposed. Each block has two teeth. The teeth of blocks 422, 424, 426, 428 are identically arranged, but in a different way from the teeth of blocks 421, 423, 425 and 427. Each of the blocks 422, 424, 426, 428 has three teeth. The teeth 47' themselves on all the blocks are identical, but the blocks 422, 424, 426, 428 have teeth in the places where the blocks 421, 423, 425, 427 have tooth spaces. In other words, the teeth of alternate blocks are turned through half a pitch about the axis of the differential. A tooth on one end of a block is aligned with a tooth space on the other end of the block in the case of the blocks 422, 424, 426 and 428.

The reason for this arrangement will be apparent from Fig. 15, which applies to spiral teeth and to straight teeth alike. It is a development to a plane of a part of the periphery of the tooth zones. The distance between the two dash and dot lines 83, 83' represents half the circumference. In the instance illustrated, both side members 50, 51 have fourteen teeth, that is, seven per half circumference. There are eight sliding blocks 42, all uniformly spaced and at equal distances from the axis of the differential. The tooth profiles of the two side members are identical and correspond to Figs. 6 and 7. Any two sliding blocks that are half the circumference apart are identical, and are in the same con-

tact position. Thus, blocks 421 and 425 are equally in engagement with both side members. Block 423 and the diametrically opposite block 427 are also equally in engagement with both side members but on opposite sides of the teeth from blocks 421 and 425. Block 422, and the diametrically opposite block 426 are in the position of closest approach to side member 51, and are in the middle of the reversal period. Block 424 and the diametrically opposite block 428 are in the middle of the 10 opposite reversal.

When the side members 50, 51 turn relative to each other, the blocks reciprocate, each at the rate indicated in the diagram of Fig. 5. They keep their phase differences, adjacent blocks staying apart a quarter of a complete reciprocation cycle.

It is seen that there are a sufficient number of phase differences to provide continuous action, even though all the sliding blocks have the same distance from the axis of the differential and are all evenly spaced, while the 20 two side members 50, 51 have the same number of teeth. Moreover, there are only two groups of sliding blocks, four blocks in each group, whose tooth position differs only on one end of the blocks.

Other tooth members than fourteen can be used on the 25 side members, and other numbers of blocks can also be employed. Preferably, however, I keep the tooth number of the side members at double an uneven number, and the number of blocks at eight. With each block containing a plurality of teeth, a differential of great strength 30 is achieved; and the surface stresses are kept low.

The arrangement indicated in Fig. 16 differs from that of Fig. 15 merely by the positions of the teeth on the ends of the sliding blocks. The blocks 42' have teeth, where the blocks 42 have tooth spaces, and tooth spaces 35 where the blocks 42 have teeth. The blocks 42' also are arranged, however, in two groups of four blocks each, the blocks of one group alternating with the blocks of the other.

In the arrangement of Fig. 16, the sliding blocks 42b 40 are all alike. To achieve phase differences in the action of the blocks, the tooth numbers of the two side members 50b and 51b are different. In the instance illustrated these side members have fourteen and sixteen teeth, respectively. Here, ten blocks 42b are used. The number 45 of blocks should be equal to the sum of the teeth of the side members, or an integral fraction thereof, in this embodiment of the invention. While, in this embodiment, the blocks are shown with a single tooth on each end, they may also be provided with a plurality of teeth. The profile inclination of the teeth of the two side members 50b, 51b depends on the tooth number, and differs on the two members, as is readily understood. The torque transmitted to the two side members would be in proportion to their tooth numbers at zero friction. Friction provides a range of torque proportions.

The arrangements shown in Figs. 15, 16 and 17 are for transmitting about equal overall torques to both driven members. On inter-axle differentials it is sometimes desirable to transmit unequal torque to the two driven members. In this case, the tooth numbers of the two side members should be altered. When the driver carries the sliding blocks the tooth numbers of the driven members should be approximately in the proportion of the torque to be transmitted to them. The arrangement of Fig. 17 is especially suitable for this case, when the difference in tooth numbers is large.

It is also possible to have one of the side members as the driver, the side member with larger number of teeth according to the principles disclosed in my patent No. 2,790,334, April 30, 1957.

From the preceding description it will be seen that surface contact is attained between the side members and the blocks, and that the block motion is at a constant 75 proportion to the turning motion of each side member

during the working contact and that there is a definite reversal period for the blocks to reverse their motions.

A particularly smooth operation of the differential is attained when the coefficient of static friction and the coefficient of sliding friction are nearly equal. Ordinarily, the coefficient is larger for static friction than for sliding friction depending upon the materials in contact. However, materials may be so selected that the difference is small. Such materials generally do not have the strength of hardened alloy steel. One such known material is graphite composition.

With the present invention, the use of materials of less strength and improved frictional properties is feasible, because the surface contact provided results in relatively low stresses. This is indicated in Fig. 19, which is a fragmentary normal section taken at right angles to the spiral teeth 48" of a side member. The teeth are faced with a material 87 of improved frictional properties. Preferably, the mating teeth are made of a single material only and have no facing. The facing may be applied to the teeth of the side members, or, if desired, to the teeth of the sliding blocks instead. Plating may also be used instead of facing, if desired.

A principal way of producing the spiral teeth is by cutting. Fig. 20 illustrates one way of cutting the teeth. The teeth of the side member 50 are here shown in normal section as in Fig. 14. The tool is indicated at 88. It has an axle 89 lying in the sectional plane of the teeth and may be a milling cutter or a grinding tool. The cutter 88 has a plurality of ring shaped cutting surfaces 92 whose cutting edges, or working portions, lie in surfaces of revolution 90, 91 whose profiles match the sectional profiles of the teeth. As the tool rotates on its axis, the known feeding motions are provided to produce involute spiral teeth, namely, the workpiece 50 is slowly turned on its axis 43 while the tool 88 is fed in the direction of the tangent 70 (Fig. 9) to the base circle of the involute. This straight line feed is timed with the turning motion of the workpiece so that the feed velocity is equal to the peripheral velocity of the workpiece at the base circle 67. The cycle is repeated for different teeth.

Instead of using a cutter such as shown at 88 in Fig. 20, a simpler cutter or grinding wheel with a single ring shaped surface may be used such as that of one of the discs 92 of the multiple disc cutter 88. The feed is then made long enough so that this single disc will cover completely the whole length of the teeth of the side member 50 to be cut.

Another way of cutting the teeth is with a form tool 93, such as shown in Fig. 21. Here the tool has a cutting motion in the direction of the tangent 70, the tool being reciprocated at a uniform rate in the direction of this line, the tool moving along the line on its cutting stroke, and being clapped out of engagement with the work at the end of the cutting stroke and returned, while clear of the work, in the opposite direction, the work rotating continuously on its axis at a uniform rate, so that the tool 93 describes the whole length of a tooth space on each stroke. A complete tool stroke, cutting and return, with the tool 93, should occur in the time that it takes for the workpiece to turn through an integral number of teeth or pitches, which number should be prime to the tooth number of the workpiece. Since the workpiece continues to turn in the same direction during the return strokes of the tool, as during the cutting strokes, the tool engages different tooth spaces on successive cutting strokes. An additional motion for indexing of the work is, therefore, unnecessary. The cut starts at the tops of the teeth; and the work is gradually fed into the tool along its axis 43, until full cutting depth is reached. The teeth are completed successively on the last cutting strokes in each tooth space, that is, are completed in the last feed position of the work.

Of course, tools with multiple cutting teeth may be also used. Also, a plurality of tools may be used to speed up production further. These would be spaced about the

work axis and cut from different sides, along lines tangent to the base circle of the involute. They would preferably cut simultaneously, and have simultaneous return strokes. At the end of a cutting stroke, the workpiece would move back along its axis, to clear the tools during the return stroke. At the end of the return stroke, the workpiece moves up to cutting position again. This is a very efficient cutting process.

Figs. 22 and 23 illustrate a further way of cutting the spiral teeth of the side members, and also those of the sliding blocks. The latter are set up in chucks or holders at such a spacing that their teeth are part of the teeth of a complete gear. Here a gear type cutter 95 is used that has a conical cutting face 96. Its axis is at 97 inclined to the face of the workpiece 50 so that cutting clearance is obtained for the cutter teeth 98, which extend parallel to the cutter axis 97. The cutting edges 99 then remain at the same distance from the cutter axis after sharpening during the whole life of the cutter. The cutting edges of the teeth are shaped conjugate to the rack profile of the section shown in Fig. 22.

In operation, using tool 95, the workpiece 50 and the cutter 95 are rotated on their respective axes 43, 97 at the inverse proportion of their tooth numbers. The cut starts with the cutter 95 adjacent one end of the teeth of the workpiece. A relative feed motion is added, in which the cutter in effect rolls along the line 70, that is tangent to the base circle of the involute teeth being produced. In this way, the teeth are cut in a continuous operation.

Among other methods, which may be employed for cutting the teeth of the side members and of the sliding blocks, it is also possible to use a taper hob of contour similar to that of milling cutter 88 of Fig. 20, and having a single thread of several convolutions.

It will be seen, then, that the desired involute spiral teeth can be produced efficiently and accurately, and in many ways.

While the invention has been described in connection with several different embodiments thereof, then, it will be understood that it is capable of further modification, and this application is intended to cover any variations, uses, or adaptations of the invention following, in general, the principles of the invention and including such departures from the present disclosure as come within known or customary practice in the art to which the invention pertains, and as fall within the scope of the invention or the limits of the appended claims.

Having thus described my invention, what I claim is:

1. A differential comprising three coaxial and relatively rotatable members, of which one is the driver and the two other members are driven members adapted to transmit torque, one of said members being disposed between the other two members, a plurality of sliding blocks being mounted on said one member for reciprocatory motion in the direction of the axis of said members, each of said blocks having teeth at its opposite ends, said other members being provided with teeth on the sides thereof facing the opposite ends, respectively, of the sliding blocks for engagement with the teeth of the sliding blocks, the teeth of said blocks and of said other members having helical side surfaces of constant lead that have profile inclinations increasing with increasing distance from the axis of said members in cylindrical sections coaxial with said members, the opposite helical side surfaces of adjacent teeth of the blocks and of the two other members being joined by arcuate portions, the arcuate portions of mating teeth being disposed to engage each other, thereby to provide for reversal of the sliding blocks adjacent the position of closest axial approach of the teeth of the blocks and said other members, and while the helical surfaces of said teeth are out of engagement with each other.

2. A differential comprising three coaxial and relatively rotatable members, of which one is the driver and the two other members are driven members adapted to transmit torque, the said driver being disposed between said

other two members, sliding blocks mounted on said driver for reciprocatory motion in the direction of the axis of said members, each of said sliding blocks having teeth at its opposite ends, each of said other members having teeth on the side thereof facing one end of the sliding blocks for engagement with the teeth provided on the sliding blocks, the profiles of the teeth of the sliding blocks changing along the length of the teeth in cylindrical sections coaxial with said members, said profiles being composed of approximately straight portions and of arcuate portions, the teeth of said other two members having arcuate portions adapted to engage the arcuate portions of the teeth of said blocks to effect reversal of the motion of the blocks.

3. A differential comprising three coaxial and relatively rotatable members, of which one is the driver and the other two members are driven members adapted to transmit torque, said driver being disposed between the other two members, and having a plurality of ways extending in the direction of its axis, a plurality of sliding blocks mounted in said ways for reciprocation therein between said other two members, a central member disposed radially inwardly of said blocks to retain said blocks in said ways, each of said sliding blocks having teeth on its opposite ends, said other two members having teeth on the sides thereof facing the ends of the sliding blocks, respectively, for engagement with the teeth of the sliding blocks, the teeth of said other two members and of said blocks being shaped to effect reciprocation cycles of the blocks composed of a uniform motion portion in each direction and of reversal portions, said sliding blocks being arranged in two groups, the blocks of one group alternating with the blocks of the other around the axis of said members, all of said blocks being disposed at the same distance from said axis, the blocks of the two groups having the teeth differently disposed on one end of said blocks.

4. A differential comprising three coaxial and relatively rotatable members, of which one is the driver and the two other members are driven members adapted to transmit torque, said driver being disposed between said other two members, a plurality of sliding blocks mounted on said driver for reciprocatory motion in the direction of the axis of said members, each of said blocks having teeth at its opposite ends, each of said other two members having teeth on its side facing one end of the sliding blocks for engagement with the teeth on said sliding blocks, the teeth on said sliding blocks and of said other two members having helical side surfaces joined by arcuate portions, the arcuate portions at the tooth bottoms being at least half as large as the helical side portions.

5. A differential comprising three coaxial and relatively rotatable members, of which one is the driver and the other two are driven members adapted to transmit torque, said driver being disposed between said two other members and having a plurality of ways which extend in the direction of its axis at equal distances therefrom and which have circular arcuate profiles, a plurality of sliding blocks mounted in said ways for reciprocation therein between said other two members, a central member disposed radially inwardly of said blocks for retaining said blocks in said ways, each of said blocks having teeth at its opposite ends, said other two members having teeth on the sides thereof facing the opposite ends, respectively, of said blocks for engagement with the teeth provided on said blocks, the teeth of said other two members and of said blocks having helical side surfaces of constant lead and having arcuate portions connecting said helical side surfaces, the tooth numbers of said other two members being equal and being double an uneven number, and said sliding blocks being arranged in two groups, the blocks of one group alternating with the other about the axis of said members, the blocks of the two groups having teeth differently arranged on one end thereof.

6. A differential comprising three coaxial and relatively rotatable members, one of which is the driver and the

other two of which are driven members adapted to transmit torque, a plurality of sliding blocks mounted on one of said members for reciprocatory motion in the direction of the axis of said members, each of said blocks having spirally arranged teeth on its opposite ends, said other two members having spirally arranged teeth on the sides thereof facing the opposite ends, respectively, of said sliding blocks for engagement of the teeth of said sliding blocks to reciprocate said sliding blocks on relative rotation of said other two members.

7. A differential comprising three coaxial and relatively rotatable members, of which one is the driver and the two other members are driven members adapted to transmit torque, said driver being disposed between said other two members, a plurality of sliding blocks mounted on said driver for reciprocation in the direction of the axis of said members, each of said sliding blocks having teeth at its opposite ends, said two other members having teeth on the sides thereof facing the opposite ends, respectively, of said sliding blocks for engagement with the teeth of said sliding blocks, to reciprocate said sliding blocks on relative rotation of said other two members, the teeth of said other two members being spirally arranged and being of opposite hand.

8. A differential according to claim 6 in which the teeth extend longitudinally, at least approximately, along involutes of a circle concentric with the axis of said members.

9. A differential according to claim 8, in which the interdental spaces of said spirally arranged teeth have a constant composite profile all along their lengths in normal sections perpendicular to the longitudinal direction of said spaces, said profiles being composed of working portions and of curved portions controlling the reversal of the sliding block motion.

10. A differential according to claim 9, in which the working portions of the tooth profiles are straight and inclined to the direction of the axis of the three members.

11. A differential according to claim 9, in which the working portions of the tooth profiles are inclined to the direction of the axis of said members at a constant angle less than 45°.

12. A differential according to claim 7, in which the spirally arranged teeth extend longitudinally, at least approximately, along involutes of a circle concentric with the axis of said members, said circle being of the same diameter on said other two members.

13. A differential according to claim 7, in which the profiles of the teeth of said other two members contain working portions and curved reversal portions, the working portions of the profiles being inclined to the direction of the axis of said members at angles smaller than 45° in normal sections perpendicular to the direction of the teeth.

14. A differential according to claim 9 in which said curved tooth profile portions are circular arcs, the tops of the teeth being of convex arcuate shape, and the bottoms of the tooth spaces being of concave arcuate shape, the radius of the concave arcs being larger than the radius of the convex arcs.

15. A differential according to claim 6 in which the working portions of the teeth of the sliding blocks engage the working portions of the teeth of said other two members with surface contact, the teeth of one of said members being faced with a material different from the material of the body of said teeth and of superior frictional properties.

16. A differential comprising three coaxial and relatively rotatable members, one of which is the driver and the other two are driven members adapted to transmit torque, a plurality of sliding blocks mounted on one of said members between the other two for reciprocatory movement in the direction of the axis of said members, each of said sliding blocks having spirally arranged teeth

at its two opposite ends, the hand of said teeth being opposite at said two ends.

17. A differential comprising three coaxial and relatively rotatable members, of which one is the driver and the other two are driven members adapted to transmit torque, a plurality of sliding blocks mounted on one of said members between the other two members for reciprocating motion in the direction of the axis of said members, each of said sliding blocks having spirally arranged teeth at its two opposite ends, the hand of said teeth being opposite at the two ends, and said teeth extending along involutes of a circle concentric with the axis of said members.

18. A differential according to claim 16 in which a tooth at one end of a sliding block is aligned with a tooth space at the other end of the block.

19. A differential comprising three coaxial and relatively rotatable members, of which one is the driver and the other two members are driven members adapted to transmit torque, a plurality of sliding blocks mounted on one of said members between the other two members for reciprocating motion in the direction of the axis of said members, each of said sliding blocks having teeth at its opposite ends, said other two members having teeth on the sides thereof facing the teeth of said blocks, respectively, the teeth of said blocks and of said other two members being, at least, approximately of involute lengthwise curvature and having side portions of straight profile, the tops of said teeth being of convex arcuate curvature, and the bottoms of the spaces between said teeth being of concave arcuate curvature and of greater radius than the tops of the teeth.

20. A differential comprising three coaxial and relatively rotatable members, of which one is the driver and the other two members are driven members adapted to transmit torque, a plurality of sliding blocks mounted on one of said members between the other two members for reciprocating motion in the direction of the axis of said members, each of said sliding blocks having teeth at its opposite ends, each of said other two members having teeth on its side facing confronting opposite ends of

the sliding blocks, respectively, for engagement with the teeth on said sliding blocks, the teeth on said sliding blocks and on said other two members being longitudinally curved and having helical side surfaces.

5 21. A differential according to claim 20 in which opposite sides of the teeth are connected both at top and bottom by arcuate portions, and in which the angular width of the bottom connecting portions at any given radial distance from the axis of a member is at least twice 10 as large as the angular width of the top connecting portions at the same radial distance from the axis of said member.

22. A differential according to claim 20 in which the opposite sides of the teeth are connected both at top and 15 bottom by arcuate portions, and in which the angular width of the bottom connecting portions of the teeth at any radial distance from the axis of a member is at least half as large as the angular width of the helical side portions of the teeth of said member at said radial distance.

23. A differential having three coaxial and relatively rotatable members, one of said members being the driving member, the two other of said members being driven members connected respectively to two axle shafts, said 25 other members having spiral teeth provided on the sides facing towards each other, a part slideable in said driving member in the direction of the axis of said members, said part having at opposite ends thereof teeth adapted to engage the teeth provided on said other two members to 30 effect driving engagement therewith, the teeth of said two other members being of opposite hand and of at least approximate involute lengthwise curvature.
